 Western Electric Company, Incorporated, New
 York, N. Y., a corporation of New York

Application July 12, 1939, Serial No. 283,922

3 Claims. (Cl. 81—121)

This invention relates to tools and more particularly to wrenches for driving screws having non-slotted heads by means of a screw driver blade.

An object of this invention is to provide a simple and practical wrench for driving screws having non-slotted heads by means of a screw driver blade.

In one embodiment of the invention for driving hexagonally headed screws by the use of a screw driver blade, which may be either of the manual or power type, there is provided an apertured body member which is tapered at one end and has a flange at its opposite end, the inner periphery of the apertured body member at its tapered end being in the form of a hexagonal socket for receiving a hexagonally shaped screw head. Fixed in the apertured body member is an insert having a slot for operatively receiving a screw driver blade. The operator in using the wrench engages the hexagonal socket with the hexagonally headed screw and engages the screw driver blade in the slot of the insert, the wrench being grasped by the knurled flanged end to steady it during the driving of the screw. In some cases it may be found desirable to provide a handle which is freely rotatable on the body member at the inner face of the flange thereof and retained in position by a collar.

Other objects and advantages of this invention will more fully appear from the following detailed description, taken in connection with the accompanying drawing, in which

Fig. 1 is a side view of a wrench embodying the features of this invention;

Figs. 2 and 3 are bottom and top plan views of the wrench shown in Fig. 1, the handle being shown fragmentarily in broken outline, and

Fig. 4 is a vertical cross-section on the line 4—4 of Fig. 3.

Referring now to the drawing wherein an embodiment of the invention is shown which is particularly adapted for driving hexagonally headed screws by means of a power screw driver, the numeral 10 indicates a body member which is of circular cross-section throughout and provided with a central shouldered aperture 11 extending longitudinally therethrough. At its lower end as viewed in the drawing, the member 10 is tapered and formed in the lower portion of the aperture 11 below a shoulder 12 is a hexagonal socket 13 for receiving a similar shaped screw head 14 (Fig. 4). The tapered lower end of the member is provided for clearance purposes to facilitate the

positioning of the socket over a screw head. Fixed to the member 10 within the aperture 11 thereof and abutting at its lower end face the shoulder 12 is a cylindrical insert 15, the insert 15 being secured to the member by a pin 16. The upper face of the insert 15 is provided with a laterally extending slot 17 for receiving the bit of a screw driver blade 18, (Fig. 4). It will be noted that the portion of the aperture 11 above the slot 17 is of sufficient length that the blade 18, which closely fits the aperture, but which may be freely entered therein, will be suitably axially supported. At its upper end the member 10 is formed with a flange 19 which is peripherally knurled as shown at 20 (Fig. 1). Freely rotatable on the body member 10 below the flange 19 is a laterally extending arm 21 carrying at its free outer end a handle 22. A collar 23 arranged below the arm and fixed to the body member 10 by a set screw 24 serves to retain the arm 21 in position.

In driving hexagonally headed screws into position, the wrench may be used either with or without the handle 22 thereon. In some cases the operator may find it more convenient to hold the wrench at a point removed from the body member 10 and at other times by merely grasping the knurled flange 19 directly in his hand. This may be influenced by the driving speed of the screw driver blade 18. If the blade is power driven it may, for safety reasons, be desirable to use the handle 22, while in the case of using a manually operated blade the handle may be dispensed with. The wrench may also be used manually without a screw driver for driving hexagonally headed screws.

From the above description, it is believed that the manner of using the wrench to drive screws having non-slotted non-circular heads by means of a screw driver blade is understood and needs no further description. The wrench embodying the features of this invention, it will be apparent, permits an operator to efficiently drive two types of screws either of the same size or of different sizes and having different types of heads by means of a screw driver either of the manual or power type.

While the features of this invention have been disclosed in a specific structure for use with a particular type of non-slotted screw head, it is, of course, understood that modifications may be made without departing from the scope of the invention as defined in the appended claims.

What is claimed is:

1. A wrench for use in driving screws having

non-slotted heads by means of a screw driver blade comprising a tubular-like body member having its inner periphery at one end formed to provide a socket portion for engaging peripheral faces of non-circular screw heads, the inner periphery at its opposite end portion being circular and a slotted circular insert fixed within said body member between the opposite ends of its inner periphery for operatively receiving in the slot a screw driver blade, said opposite end portion extending from said slotted insert for such a distance that it is effective to axially support and guide the blade into operative engagement in the slot.

2. A wrench for use in driving screws having non-slotted heads by means of a screw driver blade comprising a body member of circular cross-section having an aperture extending longitudinally therethrough, the aperture having a socket portion at one end for engaging peripheral faces of non-circular screw heads, the body member being tapered at its socket end, the opposite end thereof having a flange, an insert fixed within the aperture and provided with a slot in an end face spaced from the flange there- 25

of whereby the wall of the aperture serves to guide a screw driver blade into operative engagement in the slot, a laterally extending handle freely rotatable on the body member and arranged adjacent the inner face of the flange, and a collar fixed to the body member for retaining said handle thereon.

3. A wrench for use in driving screws having non-slotted heads by means of a screw driver blade comprising a body member of circular cross-section having an aperture extending longitudinally therethrough, the aperture having a socket portion at one end for engaging peripheral faces of non-circular screw heads, the opposite end of the body member having a flange, slotted means fixed to said body member and arranged within the aperture thereof between the socket portion and the opposite end portion for operatively receiving in the slot a screw driver blade, a laterally extending handle freely rotatable on the body member adjacent the inner face of the flange, and means for retaining said handle in operative position on the body member.

HOMER W. LARSON.
